CABLE-GRIP FOR BOGIE-TRUCKS.

1,209,591.

Specification of Letters Patent. Patented Dec. 19, 1916.

Application filed July 21, 1916. Serial No. 110,613.

To all whom it may concern:

Be it known that I, WALTER JOYCE, a subject of the King of England, residing at Fernie, in the Province of British Columbia and Dominion of Canada, have invented new and useful Improvements in Cable-Grips for Bogie-Trucks, of which the following is a specification.

This invention relates to cable grips for bogie trucks and it consists in the novel features hereinafter described and claimed.

An object of the invention is to provide a grip of simple and durable structure which is positive in its action in gripping the cable whereby the same is securely connected with the truck, the parts of the grip being so arranged that the cable may be quickly released in an emergency thereby preventing undue strain on the cable and preventing damage to the gripping mechanism. The parts of the grip mechanism are also arranged so that the cable cannot twist or become entangled with the jaws of the grip or the parts which operate the jaws in the event that the cable should become suddenly slack. With this object in view the structure includes an upper jaw with a screw threaded upon the body of the truck and adapted to move the said jaw vertically. Arms are pivoted at the under portion of the body of the truck and they carry a jaw which is adapted to impinge against the lower side of the cable whereby the same is clamped against the upper movable jaw. A bar connects the said arms together whereby they swing in unison. A releasing member is slidably mounted upon the body of the truck and means are provided for temporarily holding the said member against sliding movement. The said member is provided at its lower end with an angularly disposed section having notches which at times may receive the outer portions of the said arms whereby the said arms may swing and thus permit the jaw which is carried by the arms to release the cable.

In the accompanying drawing, Figure 1 is a longitudinal sectional view of the truck with the grip applied. Fig. 2 is a transverse sectional view of the same. Fig. 3 is a detail sectional view of the same cut on the line 3-3 of Fig. 2. Fig. 4 is a fragmentary view of a jaw used on the same with parts in section. Fig. 5 is a perspec-

tive view of the intermediate portion of a bar used on the same. Fig. 6 is a plan view of guide plates for said bar. Fig. 7 is a side view of the end portion of said bar.

As illustrated in the accompanying drawings the bogie truck to which the grip is applied comprises a body 1 which is mounted upon wheels 2 in a suitable manner. The cable which is adapted to draw the truck along the rails upon which the wheels travel is indicated at 3. Internally threaded collars 4 are applied to the intermediate portion of the body 1 and a screw shaft 5 engages the threads of the said collars and passes transversely through the same. A handle lever 6 is mounted at the upper end of the screw shaft 5 above the upper surface of the body 1. The shaft 5 is provided in the vicinity of its lower end with an annular shoulder 7 and a nut 8. The upper face of the nut 8 is spaced from the shoulder 7 of the shaft 5 thereby providing an annular groove in the vicinity of the lower end of the said shaft. A spider 9 is provided with an opening which loosely receives that portion of the shaft 5 which lies between the shoulder 7 and the nut 8 and the said spider carries a jaw 10. The jaw 10 is provided at its under side with a strip of soft metal 11, the said strip may be Babbitt metal or any other metal of a similar character. The jaw 10 and strip 11 are positioned above the upper side of the cable 3. A guide 12 depends from the lower side of the body 1 and lies at the side of the spider 9. The said guide permits the spider 9 to move vertically but restrains the same against turning movement with relation to the axis of the shaft 5.

Eyes 13 are attached to the underside of the body 1 and arms 14 in the form of bell crank levers are pivoted between the eyes 13. The arms 14 are provided at their lower inner ends with angularly disposed extensions 15 which carry a jaw 16 adapted to grip against the under side of the cable 3. The upper outer end of one of the arms 14 is weighted as at 17.

The body 1 of the truck is provided at one side with a vertically disposed opening 19, having guide strips 20 positioned in the vicinity of the upper end thereof. A locking bar 21 is slidably mounted in the opening 19 and the said bar is provided in the

vicinity of its upper end and at its opposite side with recesses 22 which slidably receive the inner edge portions of the guide strips 20. The upper end of the bar 21 projects above the upper surface of the body 1 of the truck.

The bar 21 is provided at its lower end with an angularly disposed extremity 23 which lies under a plate 24 attached to the under side of the body 1. The extension 23 is provided at its lower edge with spaced recesses 25. The recesses 25 are arranged in pairs and between the members of each pair of recesses 25 the bar 21 is provided with a downwardly disposed lug 26, the corners of which are rounded or beveled as at 27. One set of recesses 25 is adapted to receive one of the arms 14 and the other set of recesses 25 is adapted to receive the other arm 14 when the extension 23 is moved longitudinally under the plate 24 in consequence of the movement of the bar 21 along the opening 19. Guiding yokes 28 are attached to the underside of the body 1 and receive the intermediate portion of the extension 23 of the bar 21.

Locking devices are provided upon the body 1 for holding the bar 21 against movement in the opening 19. These locking devices comprise plates 29 which are secured to the body 1 at the opposite ends of the guide strips 20 and tongues 30 are hingedly connected at their outer edges with the inner edges of the plates 29 and the inner edges of the said tongues lie against the opposite sides of the bar 21 when the said tongues are swung down into horizontal positions as shown in Fig. 1 of the drawing. When either one of the tongues 30 is swung in an upward direction the bar 21 is free to be moved in the opening 19 whereby one or the other of the recesses 25 of both sets of recesses may be brought vertically above the outer ends of the arms 14 and thus the said arms may swing whereby the jaw 16 carried at the inner ends of the arms may move down from the lower side of the cable 3 and release the same. When the bar 21 is moved so that the lower edges of the lugs 26 are vertically above the outer ends of the arms 14 the outer ends of the said arms are held in depressed positions whereby the inner ends thereof are elevated and the jaw 16 which it carries at the inner ends of the bar 21 is clamped against the under side of the cable 3. The ends of the lugs 26 are rounded as at 27 in order to permit the said lugs to move readily over the outer end portions of the arms 14.

When the cable 3 is gripped between the jaws 10 and 16 the lower edges of the lugs 26 are vertically above the outer end portions of the arms 14 and in contact with the same. The screw shaft 5 is turned in the collars 4 whereby the jaw 10 is held down firm to-

ward the upper side of the cable 3. In the event that it is desired to quickly release the grip from the cable an operator swings one or the other of the tongues 30 in an upward direction thereby releasing the bar 21. The said bar is then moved along the opening 19 whereby one or the other of the recesses 25 of both sets of recesses are brought vertically above the outer end portions of the arms 14 thus permitting the outer ends of the said arms to swing vertically under the weight of the cable 3. As the said arms swing as indicated their lower ends are moved in a downward direction and the jaw 16 is moved away from the cable 3 for a sufficient distance to permit the cable to move longitudinally between the jaws 16 and 10 without moving the bogie truck. When it is desired to apply the jaws of the grip to the cable 3 the screw shaft 5 is first moved in an upward direction by turning the same in the collars 4 whereby the jaw 10 is elevated. The bar 21 is then moved along the opening 19 so that the lower edges of the lugs 26 are positioned directly above the outer end portions of the arms 14 and in contact with the same. The tongues 30 are then swung to their lowermost positions whereby the bar 21 is held against movement in the opening 19. When the outer end portions of the arms 14 are swung in a downward direction as just indicated, the inner end portions thereof are moved in an upward direction whereby the jaw 16 is carried up against the lower side of the cable 3. The screw shaft 5 is then lowered by turning the same in the collars 4 whereby the packing 11 carried at the underside of the jaw 10 is brought into contact with the upper side of the cable 3 and thus the cable is gripped between the jaws 16 and 10 and the bogie truck will move along the track rails with the cable.

Inasmuch as the spider 9 is confined between the guides 12 the jaw 10 can not turn with relation to the axis of the shaft 5 and thus it is impossible for the parts to become disarranged to such an extent as to fail to grip the cable when the device is properly manipulated. Also when the cable is released by the jaws the said jaws are in such position about the cable that in the event that the cable becomes suddenly slack it can not wind or twist about the screw shaft 5 and cause damage.

From the foregoing description taken in conjunction with the accompanying drawing it will be seen that a gripping mechanism of simple and durable structure is provided and that the same may be easily and quickly manipulated to release the cable in case of emergency and also the parts are so arranged to prevent the cable from damaging the gripping mechanism or itself in the event that the cable should become suddenly slack.

Having described the invention what is claimed is:—

1. In combination with a cable and a truck mounted for movement, a cable grip comprising a jaw located at the side of the cable, a screw shaft mounted upon the truck and connected with said jaw for raising and lowering the same, arms pivoted upon the truck, a jaw carried by said arms and lying at the opposite side of the cable from the first mentioned jaw, and a bar movably mounted upon the truck and adapted to engage the arms to hold the jaw carried thereby in gripping position against the cable.
2. In combination with a cable and a truck mounted for movement, a gripping mechanism comprising a jaw movably mounted upon the truck, means for guiding the movement of said jaw, a screw shaft threaded upon the truck and operatively connected with said jaw, arms pivoted upon the truck and carrying a jaw which lies at the side of the cable, a bar movably mounted upon the truck and having an extension provided with notches and intervening lugs adapted to engage the said arms and means mounted upon the truck for temporarily holding the bar against movement.
3. In combination with a cable and a truck mounted for movement, a gripping mechanism comprising a jaw, a shaft screw-threaded upon the truck and operatively connected with said jaw, arms pivoted upon

the truck, a jaw carried by the said arms and lying at the side of the cable, a bar connecting said arms together, a bar movably mounted upon the truck and provided with an angularly disposed extension having spaced recesses with lugs positioned between the said recesses, the said lugs adapted to engage the arms and hold the jaw mounted upon the arms in contact with the cable and means mounted upon the truck for temporarily holding the bar which is movably mounted upon the truck against movement.

4. In combination with a cable and a truck mounted for movement, a gripping device comprising a jaw, means mounted upon the truck for raising and lowering said jaw, arms pivoted upon the truck, a jaw carried by the arms and lying at the side of the cable, a bar movably mounted upon the truck and having notches with intervening lugs adapted to engage the arms to hold the jaw carried thereby in engagement with the cable, and tongues pivotally mounted upon the truck and lying at the opposite sides of the said bar and adapted to temporarily hold the said bar against movement.

In testimony whereof I affix my signature in presence of two witnesses.

WALTER JOYCE.
